TOBACCO CAN

William H. G. Murray, Syracuse, N. Y.

Application February 24, 1933, Serial No. 658,341

1 Claim. (Cl. 131—30)

This invention relates to certain improvements in cans, but more particularly to tobacco cans having means including a moisture absorbent pad for supplying moistened vapor to the tobacco

5 therein. These cans are usually made of tin or similar material and are provided with a removable cover and a horizontal partition telescopically inserted in the upper end of the can in spaced relation 10 to the cover and bottom of the can for dividing the interior of the latter into lower and upper compartments of which the upper compartment is relatively shallow to constitute what may be termed a vapor compartment while the lower 15 compartment serves to receive the tobacco.

Under these conditions, it will be evident that the tobacco in the lower compartment is accessible only after the removal of the cover and 20 partition.

25 The main object is to support a moisture absorbent pad wholly within the vapor compartment and preferably directly upon the upper surface of the partition and to provide said partition with normally closed openings adapted to be opened at will to permit the passage of the moistened vapor liberated from the pad from the upper compartment to the lower compartment for maintaining the tobacco in a reasonably moist condition.

30 In other words, I have sought to provide the partition with a plurality of tongues or tabs cut therefrom but integrally united thereto at one end so as to normally lie in their closed positions in the plane of the partition but adapted to be bent or folded upwardly and inwardly at will to form the openings and also for holding the absorbent pad in fixed relation to and upon the upper surface of the partition.

Other objects and uses relating to specific parts 40 of the can will be brought out in the following description.

In the drawing:—

Figure 1 is a perspective view of a tobacco can embodying the various features of my invention.

45 Figure 2 is an enlarged perspective view of the upper portion of the can with the cover removed, showing the partition therein with its tongues normally closed, the dotted lines indicating an absorbent sheet of blotting paper or its equivalent unfolded and lying upon the upper surface of the partition.

50 Figure 3 is a perspective view of the detached partition showing the absorbent pad in operative position thereon and the tongues opened and folded upwardly and inwardly over and upon the

adjacent edges of the pad to hold the latter in fixed relation to the partition.

Figure 4 is an enlarged vertical sectional view of the upper portion of the can taken on line 4—4, Figure 1, the absorbent pad being omitted and the tongues in their normally closed positions.

Figures 5 and 6 are transverse sectional views through the partition taken respectively on lines 5—5 and 6—6, Figure 3.

Figure 7 is a perspective view of the unfolded absorbent pad.

As illustrated this can comprises a main body 1 having a closed bottom 2 and a removable cover 3 together with a partition 4 and an absorbent pad 5. The main body 1, cover 3 and partition 4 are shown as circular and are all preferably formed of tin or equivalent material.

The body 1 is provided near its upper end with an inturned annular bead 6 which is disposed in a plane a relatively short distance from the upper end edge thereof to form a seat for the marginal edges of the partition 4 for limiting the downward movement of the partition from the top into the can.

The cover 3 is provided with an annular flange 3' adapted to fit over and upon the periphery of the upper end of the main body 1 to hermetically seal the latter. The partition 4 is of substantially the same diameter as that of the interior of the upper end of the main body 1 into which it is telescopically inserted to seat against the annular shoulder 6 and is provided with an upturned marginal flange 4' extending upwardly therefrom a distance corresponding to the distance between the annular shoulder 6 and upper edge of the main body 1.

This partition is provided with a plurality of, in this instance three, V-shaped tongues or tabs 7 cut therefrom and arranged in spaced relation about a common center some distance within the marginal edges of the partition and integrally united thereto at their inner ends.

These tongues or tabs 7 normally lie flatwise in the plane of the partition or in their closed positions when the can with the tobacco therein is supplied to the purchaser after which they may be folded or bent upwardly and inwardly to form a corresponding number of complementary openings 8 and also for retaining the pad 5 in operative position upon the upper surface of the partition, the remaining portions of the latter being imperforate.

As previously intimated, when the can with the tobacco therein is first placed in the hands

of the purchaser the tongues or tabs 7 will be in their closed positions, thus preventing the entrance of dust or other foreign matter into the lower compartment in case the cover 3 should be removed, but primarily to retain the moisture in the tobacco.

The pad 5 preferably consists of a sheet of blotting paper or equivalent material adapted to be folded along a medial line *a* to form a double thickness and is adapted to be placed upon the upper flat surface of the partition between the inner ends of the tongues or tabs 7, as shown in Figures 5 and 6 when in use.

It will be observed, however, that when the can with the tobacco therein is first sold to the purchaser, the tabs 7 will be in their closed positions and the pad 5 will be unfolded so as to extend diametrically across and upon the upper surface of the partition, as indicated by dotted lines in Figure 2 and as shown in Figure 7. This pad may bear any suitable printed matter for advertising purposes so that when unfolded, as shown in Figure 7, and by dotted lines in Figure 2, the advertising matter will be readily visible to the purchaser.

When the purchaser wishes to use the tobacco in the can, the cover 3 will first be removed after which the opposite halves of the pad 5 will be folded upon each other along the medial line *a* and then placed flatwise upon the upper surface of the partition 4 with its marginal edges closely adjacent the inner ends of the tabs 7.

These tabs are then folded upwardly and inwardly over and upon the adjacent portions of the pad, as shown in Figures 3, 5 and 6 to hold the pad in fixed relation to the partition, thereby forming the openings 8.

A finger loop 10 is pivoted to a plate 9 on the upper face of the partition 4 to provide means for removing the partition from the can when it is desired to remove tobacco from the can, said ring being normally folded flatwise upon the upper face of the partition when not in use.

Operation

When preparing the can with the tobacco therein for sale, the partition 4 is first inserted into the upper end of the can against the annular seat 6 with its tabs 7 closed or lying flatwise in the plane of the partition after which the unfolded pad 5, as shown in Figure 7, is placed upon the flat upper surface of said partition. The cover 3 is then placed in operative position and sealed to the adjacent portions of the can in the usual manner by a label or its equivalent, not shown.

When the purchaser buys the can with the tobacco therein and wishes to use some of the tobacco, the cover 3 and partition will be removed by upward displacement to permit the required amount of tobacco to be withdrawn.

Either before or after the removal of the parti-

tion, the opposite halves of the unfolded pad will be folded one upon the other and the folded pad will then be placed upon the upper surface of the partition with its edges closely adjacent the inner ends of the tabs 7 whereupon the latter may be bent upwardly and inwardly over and upon the adjacent portions of the pad to hold the latter in fixed relation to said partition.

The pad may be saturated with water before or after its application to the upper surface of the partition, after which the cover may be replaced upon the upper end of the can to prevent upward displacement of the vapor liberated from the pad and thereby to cause said vapor to pass downwardly into the lower tobacco-containing compartment through the apertures 8 with the assurance that none of the moisture from the pad will drip into the lower compartment.

The pad may be replenished with moisture from time to time as may be required after the cover has been removed without displacing the pad from the partition.

It will be noted upon references to Figures 3, 5 and 6 that aside from the apertures 8, the partition is imperforate and that the pad 5 rests upon a more imperforate portion of said partition to reduce the liability of any excess moisture passing from the pad into the lower compartment.

It will also be noted upon reference to the same figures that all of the tabs 7 are folded from their outer ends upwardly and inwardly over and upon the adjacent portion of the pad, thus leaving the openings 8 clear around the edges of the pad for the passage of vapor from the upper to the lower compartment, it being understood that the hinge plate 9 is arranged to assist in holding the pad against lateral displacement in one direction.

Although the construction shown and described is particularly simple, practical and highly efficient, it will be evident that certain changes may be made in the detail construction of the partition without departing from the spirit of the invention.

What I claim is:

In a can a closed cover therefor, a horizontal partition dividing the interior of the can into lower and upper compartments, a plurality of integral tongues carried by the partition and normally lying in the plane of the partition and adapted to be over-turned across the adjacent portions of the upper face of the partition to form a corresponding number of openings in said partition, a moisture absorbent pad resting upon the upper face of the partition and having portions thereof extended under said over-turned tongues and a hinged finger loop carried by the partition to facilitate removal thereof and disposed for edge contact with the absorbent pad to aid in retaining the latter in position.

WILLIAM H. G. MURRAY.
